UNITED STATES PATENT OFFICE.

GEORGE E. KING, OF NEWTON HIGHLANDS, MASSACHUSETTS, ASSIGNOR TO
THE GAMEWELL FIRE ALARM TELEGRAPH CO., OF NEW YORK, N. Y.

MULTIPLE-SIGNAL TRANSMITTER.

SPECIFICATION forming part of Letters Patent No. 726,944, dated May 5, 1903.

Application filed April 25, 1900. Serial No. 14,308. (No model.)

To all whom it may concern:

Be it known that I, GEORGE E. KING, of 10 Columbus Place, Newton Highlands, county of Middlesex, and State of Massachusetts, have invented an Improvement in Multiple-Signal Transmitters, of which the following description, in connection with the accompanying drawings, is a specification, like characters on the drawings representing like parts.

10 This invention relates to multiple-signal transmitters, and has for its object to improve and simplify the construction of the same in many particulars, whereby but one signal-wheel and one circuit-operating device will be required for the transmission of a number of different signals.

In accordance with this invention the signal-wheel is formed or provided with a stepped signaling-surface, and the circuit-operating device is disposed to be operated by the stepped signaling-surface of said signal-wheel, and a controlling device is provided for varying the position of said circuit-operating device relative to the signal-wheel, whereby its coöperation with said stepped signaling-surface may be varied for the transmission of the different signals. The stepped signaling-surface is preferably arranged on the signal-wheel in such manner that the 25 steps thereof will occupy different distances from the axis of the wheel, and in such event the circuit-operating device will be held by the controlling device at different distances from the axis of said signal-wheel to coöperate with said stepped signaling-surface for the transmission of the different signals.

The multiple-signal transmitter which is herein shown for the sake of illustrating this invention not only has the capability of transmitting several different signals, but also transmits the same in conjunction with a box-number signal, although so far as my invention is concerned it is not limited to a multiple-signal transmitter having such capabilities.

The multiple-signal transmitter herein shown has its signal-wheel formed or provided with a stepped signaling-surface for a number of different signals and also with a 50 signaling-surface for a box-number signal, which latter may be merely a number of

notches cut in the wheel and arranged in any predetermined manner. The multiple-signal transmitter of this type—*i. e.*, which has the capability of transmitting a number of different signals in conjunction with a box-number signal—is especially adapted for police signaling purposes, and for this purpose signal impulses of both long and short duration will be employed.

A pointer is preferably employed for operating the controlling device and a dial provided over which said pointer moves. Means are preferably provided for holding or retaining the pointer in its several different positions, and means are also preferably provided for positively locking the pointer in whatever position it may be set and retained while the transmitter is operating, and, furthermore, means are also preferably provided for automatically restoring the pointer to its normal position adapted to be operated when the locking device has disengaged the pointer.

Figure 1 shows a front elevation of the multiple-signal transmitter embodying my invention. Fig. 2 is a rear elevation of the multiple-signal transmitter shown in Fig. 1. Fig. 3 is a plan view of the multiple-signal transmitter shown in Figs. 1 and 2. Fig. 4 is a detail of the restoring device for the pointer-shaft, to be referred to. Figs. 5 to 13, inclusive, are details showing the signal-wheel, the circuit-operating device, and the controlling device for said circuit-operating device in different relative positions, to be referred to; 85 and Fig. 14 is a diagram of the number of signals which can be transmitted by the multiple-signal transmitter herein shown.

The signal-wheel a , herein shown in black as being composed of insulating material, is 90 adapted to be rotated by any suitable train, and said wheel is herein shown as secured to a shaft a' , bearing a pinion a^2 , which is engaged by a toothed gear a^3 , secured to a sleeve or hub a^4 , mounted loosely upon a shaft a^5 , 95 and said toothed wheel a^3 carries a pawl a^6 , which engages a ratchet-toothed wheel a^7 , secured to said shaft a^5 . A winding-arm b is secured to said shaft a^5 , by means of which said shaft is turned in one direction a partial revolution independently of the toothed wheel a^3 , and a mainspring b' is connected to

said shaft a^5 , which serves to restore it and at such time rotate the toothed wheel a^3 . A toothed gear c is secured to the shaft a' , which engages a pinion c' , secured to a shaft c^2 , (see dotted lines, Fig. 3,) bearing an escape-wheel c^3 , with which coöperates a suitable pallet c^4 , secured to a shaft c^5 , carrying a fan c^6 . This train when operated is designed to impart to the signal-wheel a one complete revolution, yet in lieu of the train herein shown any other suitable form or construction of train or equivalent motor mechanism may be employed. The train is herein shown as supported by the face-plates d d' .

15 The signal-wheel a herein shown is formed or provided with a signaling-surface for a box-number signal, and for simplicity a number of notches will be cut in the wheel—as, for instance, there may be a group e of three 20 notches and a group e' of two notches, and in such case the box-number signal will be "32." The signaling-surface for the box-number signal is cut in the edge of the wheel concentric to its axis. The signal-wheel a is also 25 formed or provided with a signaling-surface for a number of different signals in addition to the box-number signal, and, as herein shown, said signaling-surface is formed by cutting or otherwise providing the wheel with a number of successive steps, as e^2 e^3 e^4 e^5 , and said steps are disposed at different distances from the axis of the signal-wheel a , as shown in Fig. 2, and they are also each herein shown concentric to the axis of the wheel. Such a 30 signaling-surface is herein called a "stepped" signaling-surface. The several steps may be made of the same or of different lengths, as desired, and by referring to Fig. 2 it will be seen that three of said steps, as e^2 e^3 e^4 , are 35 made of substantially the same length, and one step, as e^5 , is made quite long, yet so far as my invention is concerned it is immaterial whether the several steps are made long or short. The signal-wheel a is thus provided 40 with two signaling-surfaces—one for the different additional signals and one for the box-number signal—and consequently any one of the different additional signals may be transmitted in conjunction with the box-number 45 signal; but the essential feature of my invention will be comprehended even if said box-number signaling-surface should be eliminated.

50 The circuit-operating device consists of two independent contact-pens f f' , adapted to engage and disengage each other to make and break the circuit, and one of said contact-pens, as f , is rigidly secured to a block f^2 , of insulating material, which is pivoted at f^3 to one of the face-plates of the frame, said block 55 thereby serving as a pivoted support for said contact-pen f , and the other contact-pen, as f' , is pivoted at f^4 to said pivoted block or support f^2 , and said pivoted contact-pen f' is held pressed into engagement with the contact-pen f by means of a spring f^5 , which is attached at one end to an arm or projection f^6

on said contact-pen f' and at the opposite end to a fixed insulated point. The contact-pens f f' each have a contact-point f^10 disposed intermediate its length, and said contact-points are arranged on the adjacent faces of said pens, so as to engage each other. One of the circuit-wires, as 2, is connected to one of said contact-pens, as to f , and the other circuit-wire, as 3, is connected to the other contact-pen, as to f' . The contact-pen f has a projection g intermediate its length which engages or coöperates with the signal-wheel a , and the contact-pen f' has a projection g' , also intermediate its length, which likewise engages or coöperates with said signal-wheel a , and said projections g and g' are disposed one in advance of the other, as shown, so that first one and then the other will drop onto the stepped portions or into the notches of the signal-wheel as said signal-wheel revolves. The spring f^5 in addition to holding the contact-pen f' in engagement with the contact-pen f exerts its action upon the pivoted block 90 or support f^2 , and thereby presses said pens into engagement with the signal-wheel. If no means were provided for otherwise controlling the position of said circuit-operating device or if the means provided for this purpose, as will be described, were thrown out of operative connection with said circuit-operating device, as shown in Fig. 13, then the 95 operation of the parts as thus far described will be as follows: As the signal-wheel a revolves, first the projection g will drop onto the first step e^2 , and the contact-pen f will thereby be moved away from the contact-pen f' , as shown in Fig. 5, and the circuit will be broken; but before said projection g passes 100 from said step e^2 and drops onto the second step e^3 the other projection g' will also drop onto said first step e^2 , as shown in Fig. 6, and the contact-pen f will thus be brought into engagement with the contact-pen f' and the 105 circuit closed. As the second, third, and fourth steps e^3 , e^4 , and e^5 pass beneath the projections g and g' the above-described operation will be repeated. Then the box-number signal-notches will arrive in position to 110 coöperate with the projections g g' of the contact-pens; but, as herein shown, said notches are differently shaped from the steps e^2 to e^5 , and as a consequence the action is somewhat 115 different. As the first notch of the box-number signal-notches passes beneath the projections g and g' , first the projection g falls into said notch, and the contact-pen f moves away from the contact-pen f' and opens the circuit; then the projection g' falls into said notch just 120 as the projection g is passing out of the notch, and the contact-pen f' moves into contact with the contact-pen f and closes the circuit, as represented in Fig. 10; then the projection g passes out of said notch and in doing so moves 125 the contact-pen f outward and also moves the contact-pen f' outward with it, maintaining the continuity of the circuit; then said projection g falls into the second notch, but owing to 130

the narrow tooth between said first and second notches the projection g' at the same time falls back into the first notch, as shown in Fig. 11, so that the continuity of the circuit is still maintained; then the projection g' passes out of the first notch preparatory to falling into the second notch while the projection g is moving along in said second notch, and the contact-pen f' is thereby moved outward or away from the contact-pen f and the circuit opened, as shown in Fig. 12; then the projection g passes out of the second notch preparatory to falling into the third notch before the projection g' falls into said second notch, thereby moving the contact-pen f' outward, closing the circuit; then the projection g falls into the third notch, and at such time the projection g' falls into the second notch and the continuity of the circuit is still maintained substantially as illustrated in Fig. 11, and on each succeeding notch the same operation is repeated. Thus one signal will be transmitted, which in diagram would be represented by four dots, followed by the box-number "32," as shown in Fig. 14.

In order that a number of different signals may be transmitted by employing but one signal-wheel a and one circuit-operating device ff' , a controlling device is provided for controlling the position of the contact-pens ff' relative to the signal-wheel, said controlling device being constructed and arranged to hold said contact-pens in different positions relative to the signal-wheel, so that they may engage or coöperate with one or more of the different steps e^2 to e^5 and also thereafter engage the box-number signal-notches, and by means of a controlling device adapted to accomplish this result the box-number signal will be transmitted in conjunction with any other signal that the transmitter may be set to transmit. The controlling device herein shown as having the capabilities above mentioned consists of a cam h , of insulating material, secured to a shaft h' , having its bearings in the frame $d d'$, and having attached to it a pointer h^2 , by means of which it may be turned at will, and the contact-pens ff' are suitably extended and provided at their extremities with projections $i i'$, which engage said cam h , and said projections $i i'$ are disposed one in advance of the other, like the projections $g g'$, and the cam h is designed to coöperate with either or both of said projections and also be moved so as not to coöperate with either one of said projections. As the cam h is turned by the pointer h^2 it will pass beneath the projections i and i' and in its different positions will obstruct the movement of the contact-pens more or less in a direction toward the signal-wheel a , except that in one position it will be out of coöoperative engagement with both of said contact-pens. In the position shown in Figs. 1 and 2 the pointer occupies its extreme position to the right and the cam h occupies a remote position from the projections $i i'$,

and if the transmitter should be operated at such time the projection g will first fall onto the first step e^2 and break the circuit, (see Fig. 5;) then the projection g' will fall onto said step e^2 and close the circuit, (see Fig. 6;) then the projection g will fall onto the second step e^3 , followed by the projection g' , thus again breaking and making the circuit; then the projection g will fall onto the third step e^4 and break the circuit; but when the projection g' arrives in position to fall onto said third step e^4 the projection i will strike upon the cam h and the contact-pen f' will be held by said cam from further movement toward the signal-wheel, and consequently the circuit will be held open, yet the contact-pen is free to follow the irregularities of the signal-wheel. The circuit will be thus held open until the projection g engages the raised portion e^{10} of the signal-wheel and the contact-pen f thereby moved into contact with the contact-pen f' , and this occurs just previous to the first notch of the box-number signaling-surface arriving in position to pass beneath the projections $g g'$. As the box-number signal-notches pass beneath the projections $g g'$ the contact-pens will be operated, as heretofore described, to break and make the circuit. Thus a signal comprising two dots and a dash followed by the box-number is transmitted. By turning the pointer toward the left a predetermined distance the transmitter will be set for the transmission of a different signal, and when the pointer is thus turned the cam h will be moved into the position shown by dotted lines, Fig. 5, and with the parts in this position if the transmitter is operated the previous operation will be repeated as the first step e^2 passes beneath the projections $g g'$; but when the second step e^3 passes beneath said projections $g g'$ both projections i and i' will strike the cam h and will be held by said cam and the circuit held open. Thus it will be seen that by turning the cam h into a number of different positions provided for it the contact-pens will be held in different positions relative to the signal-wheel and a number of different signals will be transmitted, and, as herein shown, seven different positions are provided.

In Fig. 14 a diagram is shown of seven different signals which the transmitter herein illustrated is capable of transmitting.

The pointer-shaft h' , bearing the cam h , is supported in its bearings in such manner as to be movable endwise or longitudinally for a short distance, and it has projecting laterally from it one or more projections h^4 , which move over but continuously engage a toothed ring h^4 , stationarily secured to one of the face-plates—as d' , for instance—the teeth of said ring h^4 being made V-shaped or triangular, so that said projections may move over the ring easily and when resting in any of the notches of said ring h^4 will hold the shaft from being too easily rotated. The teeth of the ring h^4 are disposed to hold the shaft h' ,

with its cam h , in the several different positions required for the transmission of the different signals. A spring h^5 is mounted upon and connected to said shaft h' , which tends to throw said shaft forward and hold it with its projections h^3 in firm engagement with the toothed ring. A restoring-spring j is also provided for said shaft h' , (see Fig. 4,) which is attached at one end to the post j^{10} and at the opposite end to a flexible band j' , which is attached to a block j^2 , secured to said shaft h' , and said restoring-spring j is made strong enough to draw up the block j^2 and turn a shaft h' whenever said shaft is permitted to turn. When the shaft h' is pressed inward by the finger or by closing the door of the box against it, the projections h^3 will be disengaged from the toothed ring h^4 , and the shaft will at such times be permitted to turn, and the restoring-spring j will at such time be free to act and restore the shaft. When the shaft h' is restored, its pointer and cam will occupy the position shown in Figs. 1 and 2. A locking device is also provided for locking the pointer-shaft h' positively in whatever position it may be set while the signal is being transmitted, and, as herein shown, said locking device consists of an arm k , mounted loosely upon the shaft a^5 , having a 30 detent at its outer extremity which engages any one of a number of notches cut or formed in a disk k' , secured to the pointer-shaft h' , and said detent-arm k is normally held out of engagement with said disk by a projection k^2 , secured to the winding-shaft a^5 , as shown in Fig. 1, and when occupying this position the pointer-shaft is free to be turned; but whenever the winding-arm is operated the projection k^2 will be removed from the arm k , 40 and said arm will at once be drawn into engagement with the toothed disk k' and held by means of a spring k^3 , which is connected to it, and when in such engaging position the pointer-shaft will be locked. The detent-arm k will remain in locking engagement with the disk k' until the winding-arm resumes its normal position, when the projection k^2 strikes said detent-arm k and disengages it from the toothed disk k' . 50 m represents a stop-pin for the pointer-shaft, which is struck by the toothed disk when said shaft resumes its normal position.

The means herein described for locking the pointer and for restoring it automatically is not herein claimed, as the same forms the subject-matter of another application filed by me, Serial No. 134,757.

I claim—

1. In a multiple-signal transmitter, a signal-wheel having a stepped signaling-surface, the steps of which are disposed at different distances from the axis of the wheel, a circuit-operating device coöperating therewith, movable relatively thereto, toward and from said axis, a controlling device for holding said circuit-operating device in different

positions relative to said signal-wheel, and means for operating said controlling device, substantially as described.

2. In a multiple-signal transmitter, a signal-wheel having a stepped signaling-surface, the steps of which are disposed at different distances from the axis of the wheel, a circuit-operating device coöperating therewith, a pivoted support for said circuit-operating device, whereby it is movable toward and from the axis of the signal-wheel, a pointer, and means operated by it for holding said circuit-operating device in different relative positions to the signal-wheel, whereby its coöperation with the stepped signaling-surface of said wheel is varied, substantially as described.

3. In a multiple-signal transmitter, a signal-wheel having a stepped signaling-surface, the steps of which are disposed at different distances from the axis of the wheel, a circuit-operating device coöperating therewith movable toward and from the axis of the signal-wheel, a cam for holding said circuit-operating device in different relative positions to the signal-wheel, whereby its coöperation with the stepped signaling-surface of said wheel is varied and means for moving said cam, substantially as described.

4. In a multiple-signal transmitter, a signal-wheel having a stepped signaling-surface, the steps of which are disposed at different distances from the axis of the wheel, a circuit-operating device movable toward and from the axis of the signal-wheel, which is operated by said signal-wheel and which comprises a pair of independently-movable contact-pens, bearing coöperating contacts, normally in engagement with each other, a controlling device for holding said circuit-operating device in different positions relative to the signal-wheel, whereby its coöperation with the stepped signaling-surface of said wheel is varied, and means for operating said controlling device, substantially as described.

5. In a multiple-signal transmitter, a signal-wheel having a stepped signaling-surface for a number of signals, the steps of which are disposed at different distances from the axis of the wheel, a circuit-operating device operated by said signal-wheel comprising two independently-movable contact-pens, a controlling device for varying the position of said circuit-operating device relative to the signal-wheel and means for operating it, substantially as described.

6. In a multiple-signal transmitter, a signal-wheel having a stepped signaling-surface for a number of signals, a circuit-operating device coöperating with said signal-wheel comprising a pair of independently-movable contact-pens f, f' each having a projection adapted to engage said signal-wheel, said projections being disposed one in advance of the other, a controlling device for

varying the position of said circuit-operating device relative to the signal-wheel consisting of a movable cam and projections on the aforesaid contact-pens f, f' disposed one in advance of the other adapted to coöperate with said cam, substantially as described.

5 In testimony whereof I have signed my

name to this specification in the presence of two subscribing witnesses.

GEORGE E. KING.
